[57] CLAIM

The ornamental design for an enclosure unit for the bed of a pick-up truck, as shown and described.

DESCRIPTION

FIG. 1 is a top plan view of an enclosure unit for the bed of a pick-up truck showing our new design;

FIG. 2 is a side elevational view thereof; FIG. 3 is a rear elevational view thereof;

FIG. 4 is an elevational view of the forward frame and window thereof taken along line 4—4 in FIG. 2; FIG. 5 is an elevational view thereof taken along line 5—5 in FIG. 2;

FIG. 6 is a top plan view of an enclosure unit for the bed of a pick-up truck showing a second embodiment of our new design, the only difference being in the addition of two hinged transparent forward cover panels; FIG. 7 is a side elevational view of FIG. 6.

FIG. 8 is a front elevational view of FIG. 6 with the hinged panels in open condition;

FIG. 9 is a top plan view of an enclosure unit for the bed of a pick-up truck showing a third embodiment of our new design, the only difference being in the addition of a one piece transparent forward cover panel;

FIG. 10 is a side elevational view of FIG. 9;

FIG. 11 is a top plan view of an enclosure unit for the bed of a pick-up truck showing a fourth embodiment of our new design, the only difference being in the addition of two hinged opaque forward cover panels;

FIG. 12 is a top plan view of an enclosure unit for the bed of a pick-up truck showing a fifth embodiment of our new design, the only difference being in the addition of two dual hinged opaque forward cover panels;

FIG. 13 is a front elevational view of FIG. 12 with the dual hinged panels in open condition.

FIG. 14 is a top plan view of an enclosure unit for the bed of a pick-up truck showing a sixth embodiment of our new design, the only difference being in the addition of a one piece opaque forward cover panel; and FIG. 15 is a side elevational view of FIG. 14 with the forward cover panel broken away to show a continuous screen thereunder.

The broken lines in the drawings are for illustrative purposes only.
